SYNCHRONOUS COMMUNICATION
SYSTEM

Harry J. Nichols, Binghamton, N. Y., assignor to
International Business Machines Corporation,
New York, N. Y., a corporation of New York

Original application May 22, 1933, Serial No.
672,161, now Patent No. 2,104,570, dated Janu-
ary 4, 1938. Divided and this application
March 25, 1937, Serial No. 132,927

7 Claims. (Cl. 178—23)

This invention relates to synchronous communication systems and particularly to single impulse printing telegraph systems and is a division of the copending application Serial No. 5 672,161, filed May 22, 1933, patented Jan. 4, 1938, No. 2,104,570.

A general object of the invention is to provide a printing telegraph system in which single signal impulses, distinguished only in respect to time, are utilized to automatically establish synchronization, to provide continuous phase correction to maintain synchronization, and to select the printing characters and printing movements.

A more specific object is to provide a synchronizing and selective system, and suitable apparatus, whereby an electric typewriter, with minor modifications and changes, can be utilized as the printing mechanism of a printing telegraph.

A further object is to provide a printing telegraph system in which the greater part of the apparatus is utilized for both sending and receiving functions with consequent advantages in economy and in simplification.

A further object is to provide a printing telegraph system in which by the simple manipulation by the operator of a single switch, the apparatus is instantly placed in the sending, receiving, or typing condition.

A further object is to provide printing telegraph apparatus utilizing a standard typewriter keyboard and with both lower case and upper case letters, figures, and characters, with automatic operation of carriage return, shift, spacer, tabulator, and back spacer, etc. so that telegraphic communications may be transmitted in the form of the usual commercial or personal letter.

A further object is to provide printing telegraph apparatus of the speed, touch, and keyboard of a standard typewriter so that typists trained to operate the ordinary typewriter may, without special training, operate the printing telegraph apparatus described in the present invention.

45 A feature of the present invention is that the typewriter utilized as the printing mechanism of the printing telegraph system herein disclosed, when not being used for the transmission or reception of messages, is equally suitable for 50 typing letters, reports, etc. of the usual nature.

A further object of the present invention is a simple calling signalling arrangement whereby initial calls can be made whether or not the driving motor is running, and while the typewriter 55 is being used for typing, and break-in calls can be made during transmission, the same apparatus being utilized to effect calling signals under the several conditions.

A further object of the invention is to automatically establish and maintain in a positive

manner and with exactness, synchronization between transmitting and receiving apparatus at separate points.

A further object is to accomplish such synchronization by means of single impulses transmitted at a definite phase position during each cycle of motion of the transmitting apparatus.

A further object is to accomplish such synchronization by means of signal impulses suitable for transmission over telephone, telegraph, or radio communication systems without special adaptation of such systems.

A further object is to maintain close synchronization of the receiving apparatus by correcting, if necessary, and in the degree necessary, the phase position of the controlled element once during each cycle of motion, ensuring that the controlled element moves at all times in close synchronization with the controlling element.

A further object is to provide a governor for driving motors for the synchronized elements which is accurate, sensitive, and quick in response, and which is compensated for temperature effects.

A further object is to provide a governor for the driving motor which permits minor speed adjustments to be made electrically without adjustment of the mechanical settings of the governor and without impairing the range of operation and accuracy of regulation of the governor.

A further object is to provide a motor speed control arrangement whereby means operable from a distance may be utilized to effect a minor adjustment of the motor speed in a predetermined amount without loss of control by the governor.

A further object is to provide a synchronizing arrangement which by simple switching methods is immediately convertible for either controlling or controlled functioning.

A further object is to provide a particular form of electromagnetic relay and associated circuit and apparatus whereby the relay may be operated by a single current impulse of short duration, and is held in the operated condition as long as similar periodic impulses are applied, and which resumes the unoperated condition when a single periodic impulse is missed.

A further object is to provide a phase correcting mechanism which is simple in construction, accurate in operation, reliable and durable, and which automatically compensates for instrumental and line retardation of signals.

A further object is to provide a smooth acting phase corrector which while in continuous operation, will not tend to change the speed of the controlled element when running in synchronization.

A further object is to provide an electromagnetic phase corrector which functions to correct

the phase position of the controlled element without physical engagement therewith.

A further object is to provide non-repeat means in the sending condition whereby only one signal is sent to the line for each operation of a type bar key lever.

A further object is to provide interlock means whereby only one key lever may be depressed at a time.

10 A further object is to provide a key latch and key release means whereby during sending operations, a key lever when depressed is retained in that position until the rotary distributor collects the corresponding signal, whereupon the key lever is released for return to the unoperated position.

15 A further object is to provide means whereby the key latch is held out of engagement with the key levers after release by collection of the signal, and thereafter as long as the key is held depressed manually, and is permitted to return to the position of engagement with all key levers when the held key is released.

20 A further object is to provide automatic cut-off means for the electronic relay whereby the current impulses corresponding to the received signal impulses are made of uniform duration irrespective of the duration of the signal impulses.

25 A further object is to provide duplex transmission means whereby break-in calls may be received when transmitting.

Other objects and features will be in part obvious and in part hereinafter pointed out in connection with the following description taken in 30 connection with the accompanying sheets of drawings forming part of this disclosure.

In the drawings, Figs. 1A and 1B, which are to be considered as parts of the same drawing, show in diagrammatic form the circuits and apparatus 35 which together with the typewriter or printer comprise a complete communication unit. Fig. 1A shows the circuits and apparatus utilized in sending, receiving, and calling. The circuits are shown in the "typing" condition, which is the 40 condition when the selector apparatus is not being used for sending and receiving, and the typewriter is available for typing. Fig. 1B shows the power rectifier providing power for the various relays, magnets, etc. comprising the selecting apparatus, and the distributor driving motor and its control.

Fig. 2 shows in diagrammatic form the circuits and apparatus utilized in sending, and for purposes of explanation is referred to as the sending 45 station or station "A".

General description

A complete installation unit consists of an electric typewriter, a typewriter control assembly, and a distributor unit assembly. The typewriter control assembly is mounted underneath and inside the typewriter frame. The distributor unit assembly is housed in a case, and is located near the typewriter. The two assemblies are connected electrically by a multiple conductor cable.

The principal items of equipment comprising a typewriter control assembly are:

- (a) The key solenoid assembly.
- (b) The key switches.
- (c) The auxiliary switch.
- (d) The key latch.
- (e) The key latch release magnet.
- (f) The key interlock.
- (g) The send-receive switch.

The principal items of equipment comprising a distributor assembly are:

- (a) The rotary distributor.
- (b) The drive motor.
- (c) The rectifier.
- (d) The clutch mechanism.
- (e) The phase-corrector arrangement.
- (f) The electronic relay.
- (g) The cut-off relay.
- (h) The non-repeat relay.
- (i) The duplex transmission arrangement.
- (j) The call circuit.
- (k) The multiple switch relay.

In Fig. 1A, the apparatus comprising the typewriter control assembly is included within the

dot-dash rectangle. All other apparatus is included in the distributor unit.

The apparatus shown in Fig. 1A performs the functions of transmitting and receiving printing impulses and synchronizing impulses, both of which classes of impulses are distributed via the rotary distributor. Referring to Figs. 1, 5, 6, the rotary distributor consists of a series of metallic segments 11, and solid metallic ring 12, both mounted on a disk 14 of insulating material, and the rotary brush arm 13, rotatably mounted on and yieldingly driven by the drive shaft 55. The ring and segments, while actually arranged in concentric circles, are shown 15 in linear development in some figures in order to simplify the diagram. The rotary brush arm 13, which makes electrical connection from ring to segments, passes across all the segments once during each resolution in a well understood manner. The drive shaft 55 is conveniently driven 20 at uniform speed by a motor 99, as hereinafter described. The brush arm 13 is shown in the rest position on segment 3.

A clutch release relay 15 is provided to stop 25 and to release the brush arm in accordance with the invention, and for illustrative purposes is shown with its armature 16 in engagement with the brush arm 13. The armature 16 also actuates springs 17 and 18 which function in connection with receiving operations.

The release relay 15 is provided with a low 30 impedance winding 20 and a high impedance winding 21 connected in series. Across the terminals of the winding 21 is connected a storing 35 condenser 22. The outer terminal of the winding 20 is connected to the positive bus 25; the outer terminal of winding 21 is connected to spring 18, to spring 182 of the send-receive switch 190, and to one terminal of the corrector magnet 36. The release relay 15 is of the quick 40 acting, slow release type, and responds quickly to a short current impulse, but holds for a prolonged period, and if supplied with properly timed impulses continues to hold in the operated 45 position as long as such impulses are regularly received. A relay which so operates is sometimes called a pulse sustained relay, and while other forms of such relays are in use, the particular form here disclosed is novel and constitutes part of the present invention. It is described in further detail hereinafter.

The power for transmission purposes and for the operation of the various relays and magnets is obtained from any suitable direct current 50 source, preferably from the rectifier assembly shown in Fig. 1B. The rectifier assembly consists of the power transfer 210, rectifier tube 211, preferably of full-wave type as shown, the filter condenser 212, and filter choke 213, all 55 connected as shown. The power transformer 210 has a primary 214, connected to the power mains 217; secondary 215 to supply heating current to the cathode of tube 211; center tapped secondary 216 to supply anode current to the tube 211; and secondary 137 with center tap 136 to supply heating 60 current to the cathode of the electronic relay 132.

The output of the rectifier is applied to the 65 terminals of the voltage divided 24a and 24b shown in Fig. 1A. The positive bus 25 is connected to the positive terminal of the voltage divider, and the negative bus 26 to the negative terminal. The zero bus 131 is connected to the zero terminal between sections 24a and 24b of the voltage divider, the section 24b thus fur-

nishing in a well understood manner a negative bias for the grid 133 of the electronic relay 132.

The elements of the electronic relay 132, which is of the grid controlled, gaseous discharge type are the grid 133, the cathode 134 and the anode or plate 135, all contained in an evacuated glass envelope, as is well understood. The center tap 136 of the cathode heating transformer 131 is connected to the zero bus 131.

In series with the plate 135 of electronic relay 10 132 is the cut-off relay 170, connected as shown, with winding 171 shunted by variable resistor 172, and provided with contacts 173 and 174. As is well known, the grid of a grid controlled gaseous discharge tube is usually unable to stop 15 the discharge when once started, and the plate current is normally cut off by disconnecting the plate supply, or by causing the plate to become negative in respect to the cathode. While either method may be used, it is preferred in the present case to cut off the plate current after a short interval by utilizing the cut-off relay to open the contacts 173-174. The variable resistor 172 permits of very exact timing of the cut-off interval, and the whole arrangement is 20 rugged and reliable. A spark suppressor arrangement may be connected across the contacts 173-174 to reduce sparking to a negligible degree.

The duplex transmission arrangement consists of the sending or output transformer 27 with 25 primary winding 28 and secondary winding 29; and the receiving or input transformer 32 with center tapped primary 33 and secondary 34. The resistor 35, of a suitable value to balance the 30 line impedance, is connected across the secondary 34, and across this resistor 35 appears the potential which overbalances the normal bias 35 on the grid 133, and trips off the electronic relay in a well understood manner. The center tap of the primary 33 is connected to one terminal of the secondary 29, the other terminal being connected to the line terminal 30.

One terminal of the primary 33 is connected to the terminal 30 while the other terminal is connected to line terminal 31 through the artificial line network AL as shown. The functioning of duplex transmission being well understood, the operation is manifest and does not require discussion beyond that which will be given hereinafter in connection with the calling 40 circuits.

The send-receive switch 190 is a three position switch, the three positions being indicated by RTS, referring respectively to the receiving, 45 typing, and sending conditions. The switch is 50 of the lever type and has one set of break-make springs, and one set of make springs. These 55 springs are numbered from 191 to 195 inclusive. In the T and S positions, the send-receive switch mechanically holds the universal bar key latch 60 151 out of engagement with the key levers 156.

The multiple switch relay 160, controlled by the send-receive switch 190, provides the automatic switching operations required to change 65 from sending condition to receiving condition and vice versa. It is provided with a single winding 161, and three sets of break-make contacts numbered from 1 to 9 inclusive. In order 70 to simplify the diagram, these contacts are shown in their natural locations in the circuit, and are numbered 1 to 9 inclusive for the purpose of identification. In series with the winding 161 is the reading condenser arrangement comprising condenser 162 and shunt resistor 163. The purpose of the reading condenser arrange- 75

ment, as is well understood in the art, is to provide a strong operating pulse in the circuit followed by a lower holding current. It also compensates in part the inductance of the circuit of which it is a part.

Synchronization

Referring to Fig. 2, the transmission of synchronizing impulses is accomplished as follows:

- 10 Assume that the brush arm 13 is frictionally driven, but is held in the rest position on segment 3 by the armature 16 of the relay 15. To start sending synchronizing signals, the send-receive switch 190 is thrown to the S position, as indicated. This completes a circuit from zero bus through reading condenser 162 through winding 161 of multiple switch relay via contacts 191-192 of send-receive switch to relay 15, through condenser 22 and winding 20 to positive bus. A strong current through this circuit operates multiple switch relay 160, breaking contacts 2-3, 5-6, 8-9 and making contacts 1-2, 4-5, 7-8. Release relay 15 is also energized, attracting armature 16 which releases brush arm 13. 25 As condensers 22 and 162 become charged, a small steady current limited by resistor 163 flows through windings 161 and 21 providing sufficient holding current to hold the multiple switch relay and release relay in the operated condition. A 30 strong operating pulse followed by low holding current is thus provided, preventing over heating of the relay windings.

On being released by armature 16, the brush arm 13 is set in rotation by the friction drive, and takes up the uniform speed of the drive shaft set by the driving motor. When the brush arm reaches segment 1, a circuit is completed from positive bus via contacts 8-1 through the pulse shaping network comprising the reading condenser 165 and shunt resistor 166 and inductance 167 in series therewith, via contacts 4-5 to segment 1, via brush arm 13 to ring 12, via contacts 2-1 through primary 28 to zero bus. For the duration of the contact of the brushes with segment 1, current flows through the circuit just traced, a corresponding signal impulse is sent to the line by the secondary 29 of the output transformer 27. This impulse, which is repeated for each revolution of the brush arm 13, is called 50 the synchronizing signal.

It is to be noted that the synchronizing signal in its passage to the line from secondary 29 passes through primary 33 via the center tap, and thus through the equal sections of primary 55 33 to the line terminals. With the artificial line AL in proper balance the currents through the sections of primary 33 are equal, and in opposition, hence no voltage is induced in the secondary 34 and the grid 133 is unaffected by 60 signals sent to the line under these conditions.

Referring to Fig. 3, the reception and application of the synchronizing signals at the receiving station is as follows:

At the receiving station, the synchronizing signals are received at the line terminals 30 and 65 31 and are applied to the terminals of primary 33 of the input transformer 32. The current from terminal 30 passing through the secondary 29 of the output transformer and the center tap 70 branch of primary 33 is negligible.

The synchronizing signal through primary 33 induces a voltage across secondary 34 and shunt resistor 35, which with proper polarity of the line terminals, opposes the bias voltage on grid 75 133. The potential of grid 133 is thus made

more positive and at a critical value depending on the characteristics of the relay 132 and the plate voltage thereon, relay 132 becomes ionized and conducting, and current flows in the plate circuit. The brush arm 13 being at rest on segment 3, a circuit is completed from zero bus through center tap 136, and transformer winding 137 through cathode 134 to plate 135 via contacts 173-174 through winding 171 via contacts 194-195 of the send-receive switch and contacts 10 3-2 to ring, via brush arm 13 to segment 3 via contacts 17-18 through condenser 22, through winding 20 to positive bus. A strong current pulse flows through this circuit, operating release relay 15 and thereafter cut-off relay 170, which 15 opens contacts 173-174, terminating the pulse. The armature 16 is pulled in, releasing the brush arm 13, and opening contacts 17-18. The flow of current through condenser 22 has charged 20 that condenser providing holding current for the high impedance winding 21, delaying the release of armature 16. The cut-off relay 170 releases quickly, being of low impedance, and being shunted by the resistor 172. Before relay 170 closes its contacts, however, the plate current has been interrupted long enough to permit the electronic relay 132 to de-ionize and the grid 133 to regain control. The electronic relay 132, with its associated cut-off relay, thus provides strong local current impulses which are 25 30 initiated by the line signals, but which are of definite duration.

When released, the brush arm 13 is set in motion by its friction drive (and clutch as is explained hereinafter) and is thereafter rotated 35 at uniform speed. Brush arm 13 having started from segment 3 shortly after the brush arm at the sending station passed segment 1, would arrive at segment 1 before the arrival of the next synchronizing signal from the sending station, 40 were it not for a slight delay in the operation of release relay 15 and the clutch mechanism.

Because of these delays which occur only during the first revolution, the lead provided by starting the brush arm from rest on segment 3 45 enables the brush arm to arrive at segment 1 as the next synchronizing signal is received. The synchronizing signal energizes the electronic relay 132 as before, but this time the circuit is completed via segment 1 as follows: via same 50 circuit as before to ring, via brush arm to segment 1, via contacts 5-6, through winding of corrector magnet 36, through condenser 22 and winding 20 to positive bus. The current pulse through this circuit replenishes the charge on 55 condenser 22, maintaining the release relay 15 in the operated condition, and energizes the corrector magnet 36. The details of the operation of the corrector magnet 36 and release relay 15 will be more fully described hereinafter. At 60 this point it is to be observed that provided the brush arm 13 arrives on segment 1 when the synchronizing signal is being applied to the grid of the electronic relay, the charge on the condenser 22 is replenished, sustaining the operation of the release relay 15, and the corrector magnet 36 is energized. If these conditions are not fulfilled, release relay 15 drops out, and during the subsequent revolution the brush arm 13 is stopped on the rest segment. If the signals 65 70 continue, the same procedure is repeated until synchronism is established.

In practice, it is found that with proper adjustment of the clutch mechanism and by setting the rest position for the brush arm at the 75

proper place, synchronism is usually established on the first revolution. Thereafter, synchronism is maintained by the corrector magnet correcting the phase angle of the receiving distributor arm to keep it in unison with the sending distributor arm. Should, for any reason, unison within approximately one half segment width be departed from, the brush arm 13 is stopped on the rest segment by reason of release relay 15 dropping out, and the synchronizing procedure is repeated when the next synchronizing pulse is received. Thus synchronism, if lost, is automatically re-established.

15 *Sending circuits and operations*

Referring to Fig. 2, the printing signal impulse transmitting apparatus includes the key switches 157 of break-make type, one for each key of the typewriter, there being 49 keys on a standard typewriter keyboard. The armature spring of each key switch is connected to an individual segment; the make springs are connected to the common key switch bus 138, as shown. The key switch bus is connected to one terminal of the non-repeat relay 140, and to spring 144 of relay 140.

Each key lever operates its associated key switch by means of an insulated push rod 150 as indicated. For transmitting purposes, each key lever when depressed is held down by the universal bar key latch 151 until released by the key release magnet 152. The universal bail 153 is positioned below and transversely across the row of key levers, being held in light contact therewith by a retractile spring (not shown). When any key is depressed, the bail 153 closes the auxiliary switch 154 by means of push rod 155. One spring of the auxiliary switch is connected to the key switch bus 138; the other spring is connected to spring 142 of non-repeat relay 140.

The non-repeat relay 140 has a low impedance winding 146, located on the heel end of the core 140, and a high impedance winding 147. In series with the winding 147 is a reading condenser arrangement consisting of the condenser 148 and shunt resistance 149.

To commence sending, the send-receive switch is thrown to the S position, and synchronizing signals are sent to the line for a few seconds to permit the receiving machine to come to synchronism as described above. Printing signals may be sent by depressing the typewriter keys as for ordinary typing.

Assuming key 5 to be depressed, the operations which result are as follows: As the key lever nears the bottom of its stroke, the mechanism of the typewriter is tripped, and the typewriter immediately types the selected character to furnish a local copy of the message. The key lever is latched down in the depressed position by the universal bar key latch 151 hooking over the end of the key lever 156. The finger can be at once removed from the key. When the key is pressed down, the push rod 150 (one for each key lever) which abuts against the lower edge of the key lever, pushes down the armature spring of its associated key switch, breaking the upper contacts and making the lower contacts. The universal bail 153 is also rotated about its axis by the movement of the key lever, and operates the single push rod 155 which closes the auxiliary switch contacts. The operation of the key switch connects the key switch bus 138 to the segment associated with the particular key

switch, in the present instance segment 5. When the brush arm 13 arrives at segment 5, a circuit is completed from positive bus, via contacts 8-7 through low impedance winding 146 of non-repeat relay 140, via contacts 144-145 to key 5 switch bus 138, via middle and lower contacts of the operated key switch to segment 5, via brush arm 13 to ring, via contacts 2-1 through primary 28 of output transformer 27 to zero bus 131. A strong current impulse flows through this circuit, its duration being determined by the time of contact of the brush arm 13 with segment 5, and a printing signal of the same duration is sent to the line by the secondary 29 of the output transformer 27.

15 *Non-repeat and key release arrangement*

The local current impulse just described, in addition to sending a printing signal to the line, also performs an important part in the non-repeat and key release actions. The local current pulse through winding 146 of non-repeat relay 140, together with the part of the pulse flowing through the high impedance winding 147, operates non-repeat relay 140, thus opening contacts 144-145, and closing contacts 144-143, and 142-141. Opening contacts 144-145 cuts off the winding 146. Closing contacts 144-143 connects one terminal of the key release solenoid 152 to the key switch bus 138 and to winding 147. Closing contacts 142-141 connects the zero bus 131 to the upper spring of the auxiliary switch and through its contacts places zero potential on the key switch bus 138. Any connected segment, except the synchronizing segment, is therefore likewise placed at zero potential and no more printing signals can be sent to the line. This constitutes the non-repeat feature.

Closing contacts 142-141 also completes a circuit from negative bus via contacts 141-142, via contacts of the auxiliary switch, through winding 147 and reading condenser 148 via contacts 8-7 to positive bus. Current through this circuit re-energizes non-repeat relay 140 and supplies holding current therefor. A second circuit is completed from positive bus via contacts 8-7 through the winding of the key release solenoid 152, through reading condenser 178 via contacts 143-144, via auxiliary switch contacts, via contacts 142-141 to zero bus. A current pulse through this circuit energizes the key release solenoid 152, whose plunger pulls the key latch 151 away from the key levers by means of the extension 182 as shown.

If the finger is removed from the freed key, 55 the key lever is drawn up by its retractile spring and the springs of the auxiliary switch 154 lift the push rod 155 and open the contacts.

Opening these contacts breaks the circuit to zero bus via contacts 142-141, and takes the holding current from the non-repeat relay 140 and key release solenoid 152, which thereupon release. Zero potential is also removed from the key switch bus 138 and any connected segment. When the key release solenoid 152 releases, the 65 key latch 151 is returned to an engageable position by the retractile spring 183. When the non-repeat 140 releases, contacts 141-143 and 143-144 are opened, and contacts 144-145 are closed, restoring initial conditions.

It is to be noted the non-repeat relay 140 and key release solenoid 152 are not released until the contacts of auxiliary switch 154 are allowed to open. Consequently, should a key be deliberately held down, repeat signals are not per- 75

mitted to be sent to the line, and the key latch is held out of engagement until the key is released. The result is that only one signal can be sent to the line for each depression of a key, and the time a key is held down is of no consequence as regards the operation of the apparatus nor as regards the accuracy of transmission. In normal operation the keys are depressed and released quickly by the operator, and are released by the key-release solenoid practically instantaneously when the printing signal is sent to the line.

Key interlock

- 15 It will be apparent from the foregoing description of sending operations, that a variable interval intervenes between the closing of a key switch and the collection of the impulse from the connected segment by the distributor brush. 20 This interval depends on the speed at which the distributor rotates and the angular travel of the brush arm in order to reach the connected segment, the interval being always less than the time of one revolution. 25 It is manifest that if two keys were pressed simultaneously, or almost simultaneously, the distributor would send out a printing signal from the first connected segment, whether or not this was the proper order for transmission. To eliminate errors of this kind, a key interlock is provided which permits only one key at a time to be depressed. While various forms of interlock have been devised and employed, the preferred form is shown in Figs. 22 and 23. This form of 30 interlock is well known, and its operation being familiar to those current with the art, detailed description is not required.

The principal parts of the interlock are the comb 235, the roller race 234, and the rollers 236, 40 one for each key lever plus one. Each key lever is located in an individual slot in the comb 235 as shown. The diameter of the rollers is exactly equal to the key space centers, and the space between all the rollers combined is slightly greater 45 than the thickness of a key lever 156. As indicated in Fig. 22, when one key lever is depressed, the slots for all the rest of the key levers are blocked.

Dual space segment arrangement

50 With a single impulse system as herein described, the duration of the signal impulse is determined by the number of segments on the distributor and the speed of rotation of the distributor arm.

There is a practical lower limit to the duration of the signal impulse, since the shorter the impulse, the higher the required frequency characteristics of the transmission system connecting the sending and receiving stations. As is well known, all communication systems have definite limits as to frequency characteristics, the limits being particularly restricted on telegraph cable circuits. One of the limitations on the 65 speed of operation of printing telegraph systems is therefore the length of the signal impulses and the number of segments on the distributor and the speed of rotation of the distributor arm are subject to this and other limitations.

70 One of the features of the present invention is the means by which the number of words transmitted in a given time is increased without a material shortening of the signal impulse. An average word in telegraphic practice consists of five letters and a space, and the speed of trans-

mission is rated on the basis of the number of equivalent average words sent per minute. On the average, since a space occurs for every five letters, one sixth of the signals are space signals. In the present invention, means are provided whereby the average time required to collect and transmit a space signal is approximately one half that required to collect and transmit other printing signals. The means is to provide two segments for the space signal located approximately diametrically opposite on the distributor. These segments are connected in parallel, and either one can transmit or receive a space signal. The arrangement is indicated by the connection of segments 8 and 36 in Fig. 1A. Thus, when the space bar is depressed, the distributor arm on the average moves only one quarter revolution until the signal is collected; for other signals an average movement of one half a revolution is required. As an example of the advantage of this improvement, assume that the distributor arm makes 4 revolutions per second. The theoretical average speed of transmission, using only one space segment, would be:

$$\frac{4 \times 60}{(6 \times \frac{1}{2})} = 80 \text{ words per minute}$$

Using the dual space segment arrangement, the theoretical average speed would be:

$$\frac{4 \times 60}{\frac{5}{2} + \frac{1}{4}} = 87 \text{ words per minute (approx.)}$$

Sine wave impulse feature

As is well understood, a sine wave impulse undergoes the minimum distortion in transmission, and permits the design of circuits of minimum impedance for a given frequency. Also, the problem of suppressing sparking at contacts is rendered less difficult. One of the features of the present invention is means whereby virtual sine wave impulses are generated in the local circuits, and the signals sent to the line are of approximate sine wave form. In the sending circuit, the means for forming sine wave impulses comprise the storage condenser 186 across the voltage divider 24a and in series with section 24b, together with wave shaping arrangements and proper design of the circuit constants of inductance, resistance, and capacity. In the sending circuit connected to segment 1 for generating synchronizing impulses, the wave shaping arrangement comprises the reading condenser 165 and shunt resistor 166, and inductance 167 in series therewith, together with the storage condenser 186 and the primary 28 of the output transformer 27, cooperate to produce a sine wave impulse in this circuit, and virtual sine wave synchronizing signals are sent to the line. In the printing signal circuits, the storage condenser 186, the reading condenser 148, windings 146 and 147 of non-repeat relay 140, and the primary 28 cooperate to produce sine wave impulses in these circuits.

Receiving circuits and operations

Synchronism having been established as previously described, and the brush arms at the receiving and sending stations being in unison, printing signals may be sent to the receiving station as described in connection with sending operations.

Referring to Fig. 3, the printing signals when received are impressed on the primary 33 of the input transformer 32, and potential variations from the secondary 34 cause a drop across re-

sistor 35 opposing the negative bias on grid 133, which on becoming sufficiently positive triggers off the electronic relay 132 which becomes conducting. A circuit is thus completed from zero bus 131 through center tap 136, and winding 137, from cathode 134 to anode 135, via contacts 173-174 through winding 171, via contacts 194-195, via contacts 3-2 to ring, via brush arm 13 to the particular segment with which the 5 brushes of distributor arm 13 are in contact. From this segment, of which segment 5 may be considered as an example, the circuit continues via the middle and upper contacts of key switch 157 to winding 159 of key magnet 158 to key 10 magnet bus 139, thence via contacts 8-9 to positive bus 25. The pulse through this circuit energizes cut-off relay 170 and key magnet 158, whose plunger is attracted, stretching spring link 184 which pulls down the key lever to which it is 15 attached. The key lever trips the typewriter mechanism (not shown) and the character is printed. As the key lever nears the end of its downward travel, the push rod 150 breaks the middle and upper key switch contacts. Owing 20 to the inductance of the key magnet, the inertia of the plunger and the key lever, and the action of the spring link 184, the breaking of the key switch contacts is retarded and the circuit is actually broken by the opening of the contacts 25 30 173-174 by the cut-off relay 170. The length of the printing impulses and the synchronizing impulses is thus determined by the setting of the cut-off relay 170, and this relay is in practice adjusted to cut-off shortly before the termination 35 of the line signal. In this way, the circuit is normally broken at contacts 173-174, which may be provided with a spark suppressor arrangement to suppress sparking at these contacts. With perfect unison, the circuit is broken before the 40 brushes leave the connected segment, hence 45 sparking at the distributor is minimized, such sparking as occurs being principally due to the inductive energy in the key magnet. The sparking at the contacts of the key switches is negligible.

It is to be observed that when receiving printing signals, the key magnet energized is that which is connected to the segment being contacted by brush arm 13. When the brush arms 50 at the sending and receiving stations are in unison, the key magnet selected at the receiving station will correspond with the key switch closed at the receiving station. Accuracy in selection thus depends on close unison of the brush arms, 55 and cutting off the printing impulse before the brush arm at the receiving station has carried over into contact with the adjacent segment. The corrector magnet provides the required close unison, and the cut-off relay terminates the impulses, both synchronizing and printing, after a definite interval. The line retardation and ionizing time of the electronic relay are not material factors with the present invention, since the synchronizing signals are subject of the same delay as are the printing signals, and the corrector magnet automatically compensates for this delay. Likewise, any instrumental delays from line 60 relays, etc. interposed in the transmission system are automatically compensated for.

70 While for illustrative purposes, the sending and receiving stations are represented as being connected by a transmission line consisting of one wire and ground, it is to be understood that any form of communication system, such as telephone, telegraph, or radio or cable circuits may

be used, automatic compensation of transmission delays provided by the invention being an important factor in its ready adaptation to various forms of communication circuits.

Calling circuits and operations

Referring to Fig. 4, which shows the calling circuits separated from the other circuits, the apparatus receiving the calling signals from the line include the artificial line AL, and the primary 33 of the input transformer 32. The apparatus for utilizing the calling signals comprise the secondary 34 of the input transformer, the glow lamp 202, the electronic relay 132, the cut-out relay 170, the send-receive switch 190, and 10 the call bell 201. The send-receive switch 190 controls the calling circuit. When the send-receive switch is in either the "typing" or "sending" 15 positions, the call bell is connected in the calling circuit; when the send-receive switch is in the "receiving" position, the call bell is disconnected. 20

Assume the send-receive switch at the receiving station is in a typing position and that the machine is being used for typing purposes. To call, the sending station throws the send-receive 25 switch to the S position and sends synchronizing signals to the line as described under synchronization. From terminals 30-31 of the receiving station, the signals traverse the circuit from terminal 30 through primary 33 through artificial 30 line AL to terminal 31. Some current flows through secondary 29, but the primary 28 is open, and this current is ineffective. The signal impulses through the primary 33 induce potential variations in the secondary 34 and these variations are applied to the grid 133 as previously described. The grid 133 ionizes the electronic 35 relay 132 which becomes conducting, and a circuit is completed from zero bus 131 through electronic relay 132 via contacts 173-174, through 40 winding 171 of cut-off relay 170, via contacts 194-193 through winding of the call bell 201 to positive bus 25. Current flowing in this circuit energizes the call bell, and also cut-off relay 170, which operates and breaks the circuit in the usual 45 way. This action is repeated as each synchronizing impulse is received. Since the cut-off relay opens the circuit after each pulse, the interrupter in the bell can be dispensed with.

To stop the bell, the send-receive switch is 50 thrown to the receive position which opens the calling circuit, and establishes the receiving circuit as shown in Fig. 3. The receiving distributor is then synchronized, as previously described, and transmission begins.

55 The second calling situation is that existing when a station is sending and the receiving station wishes for some reason to call back. This is the so-called "break-in" call. Referring to Figs. 2 and 3, the circuit conditions at the sending 60 station are shown in Fig. 2, those at the receiving station in Fig. 3. To make the break-in signal, the receiving station throws the send-receive switch to the send position, changing its circuit conditions to those shown in Fig. 2, and synchronizing signals are immediately sent to the line in the reverse direction, i. e., from receiving station to sending station. The calling circuit at the sending station is in the condition shown in Fig. 4, the send-receive switch being in the position shown by dotted lines. Due to the duplex arrangement of the transformers, previously described, the received synchronizing signals actuate the electronic relay 132, and the call bell is energized as previously described. Due to the 70 75

balancing effect of the artificial line, the outgoing signals do not actuate the electronic relay.

Without further analysis, it will be evident that a called station can acknowledge the call, and signal ready, by throwing the send-receive switch momentarily to the send position in answering a call, and before moving to the receive position. The calling station is thus informed of the readiness of the called station, and can start sending 10 without delay.

In the foregoing, the call signal device was described as a bell. It is obvious, however, that any of the usual audible or visual signalling devices, such as buzzers, gongs, annunciators, 15 lamps, etc., can be employed, the power in the calling circuit being adequate for operating such devices and such variations are included within the scope of the invention as defined by the generic claims.

20 It will be observed that in the foregoing description of the calling system, two-way communication circuits were assumed. When one-way circuits, such as radio circuits, are employed, break-in and call-back signals are not usually 25 feasible and the usual calling conventions for one-way circuits must be observed.

It is further to be observed that with the calling system described, it is not necessary that the distributor motor be turned on, but that power 30 must be supplied to the electronic relay. To receive a calling signal without having power on the electronic relay, a small neon glow lamp 202 is connected into the calling circuit at some convenient point, as for example across the secondary 35 aray 35 as indicated in Fig. 4.

It will be perceived that I have provided a simple and flexible calling system which is very economical in cost, and which possesses numerous advantages.

40 The electronic relay

The electronic relay 132 may be of the hot-cathode type, as shown, or of the cold-cathode type, in which case the cathode heating transformer 137 is not required. As is well known, 45 the grid potentials sufficing to ionize electronic relays is comparatively low, and they are therefore susceptible to stray potentials, inductive effects, etc. and for best results, measures to insure stability in operation are desirable. In the present invention, stabilizing measures which have been found effective comprise the grid current limiting resistor 203, the grid to cathode by-pass condenser 204, and the grid potential stabilizer 50 arrangement consisting of the ballast condenser 205 and the ballast resistor 206.

The function of the current limiting resistor 203 is to limit the grid current to moderate amounts during the periods when the grid is 55 positive. It is preferably of a comparatively high value, values of 50,000 to 500,000 ohms giving good results. The function of the grid to cathode by-pass condenser 204 is to by-pass high frequency and inductive potentials, preventing ionization of the relay from these effects. This condenser may be of comparatively small size, capacities of the order of .0025 mfd. having been found to give good results.

The function of the ballast condenser 205 and 70 ballast resistor 206 is to preserve uniform bias potentials on the grid 133. When local impulses occur, part of the charge on storage condenser 186 is lost, and current flowing through bias resistor 24b to replenish the charge on condenser 75 186 causes a momentary variation in drop across

24b. The potential across ballast condenser 205, and consequently the grid bias potential, remain almost constant during such variations, since because of ballast resistor 206, any change in the charge on condenser 205 is retarded. The time 5 constant of the combination of condenser 205 and resistor 206 is proportional to the product of their values, hence a wide range of values is possible. The arrangement permits an electronic relay to be operated from a voltage divider of 10 momentarily fluctuating voltage with practically the same stability as is obtained with a battery to supply bias to the grid of the relay.

15 The rotary distributor and phase corrector

In Figs. 5 and 6, which show in detail the rotary distributor and corrector magnet assemblies, the rotary distributor is seen to consist of a hub 37, with diametrically positioned contactor arm 38 and corrector arm 39 mounted in cross holes 40 therein by suitable holding means such as set screws 41. On the contactor arm 38 is mounted a link 42 of insulating material by means of screw 43, extending axially into the outer end of contactor arm 38. On the projecting end of link 42 is mounted the brush arm 13 by means of a screw 44, extending axially into arm 13. The outer end of the arm 13 is cut into half-cylindrical section, and on the cut section is mounted the half-cylindrical brush 30 clamp 45. Between the flat surface of arm 13 and clamp 45 are clamped two flexible metallic brushes 46 by means of a screw 47. The outer ends of the brushes 46 slope rearwardly and contact the segments 11 and ring 12 with a light pressure. The brushes are conveniently made of copper braid, bundles of small copper wires, or silver strips, as is commonly practiced in the telegraphic art.

The corrector arm 39 carries at its outer end 40 the corrector bar 49 of magnetic material, preferably a metal or alloy of low magnetic permeability such as soft pure iron, or magnetic nickel alloy. The corrector bar may have a variety of shapes, the preferred shape being shown in Figs. 45 6 and 7. The corrector bar should be rigidly mounted on the corrector arm, and is so mounted conveniently by positioning in a slot cut in the end of the corrector arm, and secured therein by one or more screws 48 (one being shown) 50 as clearly indicated. In the preferred form, the location and length of the corrector bar 49 is such that on rotation of the distributor hub, the corrector bar passes end-wise between the pole pieces 50 with a small air-gap at each end. The 55 air-gap which has been found preferable is of the order of .025 inch.

The corrector magnet 36 is preferably mounted on a bracket 52, adjustable in an arc by means of curved slots 53 and screw 54, so that 60 the poles 50 of the corrector magnet 36 may be adjustable sidewise concentrically with the drive shaft 55. By this adjustment, the corrector magnet 36 may be moved in relation to the synchronizing segment 1. The need for this adjustment will be evident when it is considered that a small interval of time is required for the flux in the corrector magnet 36 to build up in response to the synchronizing current impulses, this interval in part depending upon the inductance in the corrector magnet circuit. During this small interval, the distributor arm moves in the direction of rotation, hence the corrector magnet for proper action should be displaced angularly in the same direction by a slight amount 65 70 75

in excess of the mechanical angle of 180° represented by the axis of the corrector arm and the line of contact of the brushes 46. The best adjustment of the position of the corrector magnet 36 is readily determined by trial and may thereafter be left fixed.

The best proportions for the faces of the poles of the corrector magnet, and for the corrector bar may be in part determined by analysis, but refinement in the design of these parts is most readily obtained by experiment. The result desired is that the corrector bar should pass between the poles of the corrector magnet without material retardation or acceleration when the distributor arm is in perfect synchronism with that of the sending station, but shall be subject to corrective action when the synchronous relation is departed from.

Figs. 8 and 9 show a modification of the corrector bar-corrector magnet arrangement, in which the corrector 49 passes in front of the poles 50 of the corrector magnet 36. The poles 50 are in this case narrowed at the face nearest the corrector bar to substantially the width of the corrector bar, as shown. On analysis, it will be evident that as the corrector bar approaches or departs from the poles 50, a tangential magnetic pull will be exerted. The correcting action will therefore be the same as for the forms shown in Figs. 6 and 7. The strong radial pull, however, requires increased rigidity for the drive shaft to resist this unbalanced pull. This unbalanced radial pull, together with the fact that the corrector-bar 49 of the form shown in Figs. 8 and 9 is for the same magnetic efficiency heavier than that shown in Figs. 6 and 7 represent comparative disadvantages for the first named type.

Another possible modification of the form of the corrector bar and corrector magnet poles is shown in Figs. 10 and 11. Since this modification represents a combination of those previously discussed, its action is manifest and further discussion is unnecessary.

Various other combinations of pole pieces and corrector bar shapes are possible, and such variations are included within the scope of the invention as defined by the generic claims.

Fig. 12 shows a typical tangential magnetic pull-displacement curve. The ordinates represent, in arbitrary units, the tangential component of the magnetic attraction of the poles 50 on the corrector bar 49 shown in Figs. 6 and 7. The abscissae represent the displacement of the vertical median plane of the corrector bar from the median plane of the corrector magnet poles. The arrows within the diagram indicate that the pull is towards the median plane of the corrector magnet. From this curve it is evident that a tangential force tends to hold the corrector bar in alignment with the corrector magnet poles. Assuming the corrector magnet to be energized by uniform direct current, this force depends on the amount of the displacement of the corrector bar from the median plane of the corrector poles, increasing rapidly to a peak value and then declining. For exact coincidence of the median plane of the corrector bar with that of the corrector magnet the tangential force disappears. This region in the curve is termed the "notch" and clearly indicates the nature of the corrective action of the corrector magnet. The curve shown is a static curve at a particular value of current. Other values of current produce a family of curves of the same general form. When

the corrector bar is passed rapidly between the poles, some distortion of the curve doubtless occurs. Also, the synchronizing current impulse is of a general sine-wave form, causing a rise and fall in the magnetizing force of the magnet. Practical experience indicates, however, that the curve shown in Fig. 12 represents substantially the corrective action of the corrector magnet on the corrector bar to maintain the latter in unison with the sending distributor arm.

Referring to Fig. 6 which shows details of the drive shaft hub assembly, the hub 31, preferably made of a light metal such as aluminum, has a cylindrical axial bore 56 fitted to give a free turning fit on the drive shaft 55. A drive collar 57 is fixed on the drive shaft 55 by suitable adjustment means such as the set screw 58. To the periphery of the collar 57 is cemented or vulcanized a rubber roll 59. Next is placed over the drive shaft a washer 61, preferably of steel. Upon this washer rests the hub collar 62, to which is cemented or vulcanized the rubber roll 63. The hub collar 62 has an upward extending annular section which extends into a counter-bored cylindrical cavity in the lower end of the hub 31, and is adjustably secured therein by any preferred means, as by the set screw 64. Assembled on the hub collar 62 next to the hub is the stop flange 65, being secured thereto by welding or other preferred means. The stop flange is extended radially at one point on its periphery to form an ear 66 as shown. The purpose of this construction is to permit of ready angular adjustment of the ear 66 on the stop flange 65 in relation to the distributor arm to enable proper setting of the rest position of the brushes 46 to be made.

To the top of the hub 17 is demountably assembled the friction cup 67, held from rotating by a sliding pin and hole arrangement (not shown). The upper portion of the friction cup is counter-bored to contain a friction pad 68 of soft material, preferably a firm felt ring. The upper end of the drive shaft 55 is reduced in section and is threaded. Thereon is screwed the adjustable friction nut 69, provided with a radial set screw 71 to retain the friction nut in the position of adjustment.

The friction pad 68 is liberally oiled and on being compressed, oil works down the shaft along the bore of the hub to the friction washer 61 to provide lubrication of these parts. The friction nut is adjusted until the distributor arm is driven with little if any slip. The arrangement shown permits of an easily adjustable, smooth acting friction drive for the distributor arm which is found to stay in adjustment for extended periods.

The clutch mechanism

Referring to Figs. 13, 14, 15 which show the assembly of mechanism by which synchronism is established, adjacent to the rolls 59 and 63 and with axis parallel with the shaft 55 is rotatably mounted the double cam 72 located so as to engage circumferentially the rolls 59 and 63. The cam 72 rotates on the spindle 73 mounted perpendicularly on plate 14 by riveting. Underneath the cam 72, slidably mounted on plate 14, is the cam detent 75. The cam detent 75 pivots at one end on the pivot pin 76. In the middle section of the cam detent is a curved slot 77, through which extends the stud screw 78. This screw prevents the cam detent from rising out of place and limits its travel. The free end of the cam detent is bifurcated, and the two prongs turned up to form pawls 80 and 81 which alternately engage the

lower stop 82 on the double cam 72. Extending through the cam detent 75, between the slot 71 and the pin 76, is located a small hole 83, through which is assembled the crank-shaped 5 end of the operating link 84. The other end of link 84 is threaded and to it is assembled the adjustable clevis 85. The clevis 85 is assembled to the armature 16 of the release relay 15 by a pin 86.

10 The cam 72 is provided with a projecting upper stop 87, located on the top surface, and diametrically opposite the lower stop 82. This upper stop 87 is engageable by the ear 66 of the stop flange 65 in one position of the cam 72. The diameter 15 of the cam 72 is reduced at the middle by the groove 90 (see Fig. 16). Extending into and across the groove 90 is the accelerating spring 91 which bears near its outer end against the accelerating pin 92, as shown. The accelerating 20 spring 91 is looped in several turns around a pin 93 rigidly mounted in the plate 74. The fixed end 94 of the accelerating spring 91 bears against the pivot pin 76. The accelerating pin is so formed that when assembled as shown, the free 25 end bears with moderate pressure against the accelerating pin 92.

The circumference of the double cam is serrated with a straight knurl except over an arc of approximately 90° in the region of the upper 30 stop 87, where the radius is reduced and the cam edges are left smooth. This arc of the cam clears the rolls 59 and 63 when adjacent thereto.

The operation of the clutch mechanism is as follows: When the parts of the mechanism are 35 in the position shown in Fig. 13, the short pawl 80 engages the lower stop 82, stopping the double cam in such position that the upper stop 87 is virtually on the line of centers of the rolls 59 and 63 and the double cam 72. In this position the 40 smooth edge of the cam is adjacent the rolls 59 and 63, providing clearance therebetween. The hub 37 can therefore continue rotation until the ear 56 engages the upper stop 87, which stops the motion of the hub and the brush arm is 45 stopped in the rest position on segment 3 as shown in Fig. 5. Since the hub 37 is frictionally driven, the drive shaft 55 and the roll 59 continue in rotation.

Assuming now that the release relay 15 is energized, the armature 16 pulls the link 84 which in turn draws the cam detent 75 away from the cam. The short pawl 80 is thus pulled out of engagement with the lower stop 82, releasing the cam 72. The detent 75 is drawn to the position 55 shown in Fig. 14. The accelerating spring 91 by exerting force on the accelerating pin 92 causes the cam 72 to rotate quickly in a counterclockwise direction. This rotation of the cam 72 brings its serrated edges into engagement simultaneously 60 with rolls 59 and 63. Since roll 59 is secured to the drive collar 57, and roll 63 to the hub collar 62, when the cam serrations grip the rubber rolls 59 and 63, the hub 37 is virtually locked to the drive shaft. It is to be noted that this is not a 65 friction clutch, since the serrated cam edges mesh with the rolls 59 and 63 without slipping and as though geared thereto.

The cam 72 is rotated by reason of being engaged by roll 59, and the upper stop 87 is rotated 70 away from the ear 66, removing these members from engagement. The cam 72 continues to rotate until it reaches the position shown in Fig. 14, when the lower stop 82 comes into engagement with the long pawl 81, stopping the cam. In this position the smooth arc is adjacent the rolls 59

and 63 and the hub 37 is freely driven by the friction drive previously described. The ear 66 passes clear of the upper stop 87 as shown in Fig. 14.

Should the release relay 15 become deenergized, 5 the armature 16 is pushed back by spring 17, and link 84 pushes the detent 75 back into the position shown in Fig. 13, disengaging pawl 81 and lower stop 82. The accelerating spring 91, which has been placed in tension on the accelerating 10 pin 92 by the rotation of cam 72, now rotates cam 72 through a short arc, bringing cam 72 in the position shown in Fig. 13. When the ear 66 arrives at the upper stop 87, the hub is stopped and conditions are restored as at the beginning of 15 the cycle described above.

It is to be observed that the mechanism just described provides a definite, but adjustable, stop or rest position for the brush arm 13; that on operation of the release relay 15 the driving shaft 20 55 and hub 37 are quickly clutched together in a positive manner to bring the hub 37 up to the speed of the drive shaft; that the positive action of a gear clutch is obtained without the difficulty of possible clashing of gears if engaged in the 25 wrong position; and that the clutch action is controlled with the application of but little force on the part of the clutch release magnet. The accelerating spring 91 minimizes the interval required for the clutch to act after the release relay 30 35 is energized.

It is obviously possible to eliminate the clutch mechanism and cause the link 84 to engage and stop the ear 66 without the intervention of additional mechanism. The frictional torque of the 40 friction drive is, however, restricted to a small amount, otherwise the pull of the corrector magnet 36 will be insufficient to overcome the frictional torque. The proper frictional torque for good correcting action is incapable of accelerating 45 the hub 37 and the distributor arms mounted thereon without considerable slip occurring. Furthermore, in practice it is found that such slip during acceleration is variable to such an extent that the corrector arm bar 49 does not 50 reliably come into position between the poles 50 when the hub is accelerated solely by the normal frictional driving torque. The object of the clutch mechanism is therefore to establish synchronization in a single revolution in a certain and 55 reliable manner.

The release relay

Referring to Figs. 13 and 17, which show the release relay 15 and associated parts of the circuit, comprising part of the present invention, the relay proper is of a well known type, commonly referred to as a telephone relay. On the core 15 is assembled a low resistance coil 20 of a comparatively few turns concentrated at the armature end of the core. Next in order is a high resistance winding 21 of several thousand turns, occupying the central part of the core length. At the heel end of the core is assembled a concentric sleeve or "slug" of copper 23. The coils 65 20 and 21 are wound in the same direction and the adjacent terminals of the windings are connected together in series connection.

The release relay as thus far described is a well known type commonly classified as a double-wound slow releasing relay. When supplied with a pulse of sufficient magnitude and of considerable duration, such relays normally operate in from .004 to .006 second, and release in from .08 to .28 second after being fully energized. In high 70 75

speed printing telegraphs, however, the signal impulses are of very short duration, the complete pulse interval being of the order of .003 to .005 second. A relay of the usual type designed to have a release time of .25 to .30 second, i. e. the time required for the distributor arm to make one revolution, plus a margin, will not respond to impulses of short duration, for the reason that the copper slug required to produce such delay in release time is of comparatively large size, and prevents by its reaction the storing of the required amount of magnetic energy in the magnetic structure of the relay. To overcome this difficulty, which is inherent with this type of relay, a storing condenser 22 is connected in shunt across the terminals of the high resistance winding 21. This condenser should normally be of considerable capacity, values of from 2 to 16 microfarads, depending on the release time desired, having been found to give good results. With this condenser added to the combination, the operation of the release relay 15 in response to current impulses of short duration is as follows: When the synchronizing pulse is applied to the circuit shown in Fig. 17, a rush of current flows through the low resistance coil 20 into the storing condenser 22, which because of its large capacity offers comparatively little impedance to such rush of current, particularly at the beginning. This rush of current through coil 20 magnetizes the core 15 at the armature end and attracts the armature 16. The reaction of the high resistance coil 21 and the slug 23 are ineffective to prevent the coil 20 from magnetizing the armature end of the coil 15, because of their remoteness from this section of the core, and because of the high inductance of the coil 21. The counter E. M. F. generated by transformer action in coil 21 by the current in coil 20 does not oppose the current in coil 20, but is utilized to aid in charging condenser 22. The maximum energy is thus stored in the charge of condenser 22. On the decay of the pulse current, this energy, combined with that stored in the coil 21 and the slug 23, operate to maintain the magnetic flux in the core, in accordance with Lenz's law. The armature is thus held firmly to the core during the decay of the pulse and thereafter. The release time is controlled by the amount of charge on the condenser 22 and the time required for the current through coil 21, due to this charge, to decay until the holding current in the coil 21 drops below minimum value. The variable resistor 19, located in the circuit as shown in Fig. 17, provides a convenient means for adjusting electrically the release time of the relay without the necessity of change in design, or mechanical adjustment of the relay. It is to be noted that the location of resistor 19 in the circuit is such as not to interfere with the operating pulse, but acts only to retard the discharge of condenser 22 through the coil 21. Where such adjustment of the release time is not required, the resistor 22 may be omitted without detriment, provided the resistance required to produce the release time desired is incorporated in the coil 21.

It is to be noted that the role of the slug 23 is materially different in the present invention from that played in the types of slow release relays heretofore known. In such prior types, the release time is mainly dependent on the energy induced in the slug (stored in the form of circulating current) by change in the magnetic flux in the core 15. In the present invention, the release time is controlled almost exclusively by the

charge on the condenser 22 and the characteristics of the coil 21, any contribution from the slug being inconsequential. For certain values of capacity of the condenser 22 and of inductance and resistance of the coil 21, an oscillatory discharge of energy between the condenser 22 and coil 21 may occur. For other combinations, a reversal of flux may occur when the circuit including the windings of the release relay is broken. In such instances the relay may release the armature 16 momentarily, causing an unwanted drop out. The slug 23, by its damping action, opposes sudden magnetic changes, and causes the relay to hold without chatter or release during transient conditions in the circuit. The damping action of the slug 23 is of importance in cases where the relay tends to chatter or drop out momentarily. In cases where such tendencies do not exist, the slug 23 may be dispensed with.

The relay described is capable of quick operation when supplied with impulses of short duration; of holding firmly over periods of as much as a second after the energizing current has been cut off; and of being reenergized by short current pulses recurring periodically. It is further characterized by the principle of storing the energy for holding the relay in an operated condition in an associated condenser, which condenser is charged partly by the pulse current and partly by energy generated in the holding winding by transformer action from the operating winding. The characteristics and principle of operation of this relay are such as to constitute a generic class distinguished from prior forms of quick acting, slow release relays.

35

The motor governor

Referring to Figs. 18 to 21 inclusive, the motor governor 100 which is of the electrical type, consists of a disk 101 of insulating material, mounted on a hub 102, which in turn is mounted on the motor shaft 103 by set screw 104. On the periphery of the disk 101 are mounted two slip rings, 104 and 105, by which means current is led to the governor. The contact bracket 107 is held in place by two screws 110 which pass through the disk 101 and terminate in slip ring 104 making electrical contact therewith. In the upturned portion of the bracket 107 is threaded the adjustable contact screw 111 having at the end a contact 112.

The governor bracket 108 mounts the kinetic members, namely, the tongue 113 and the governor spring 114. The tongue 113 is of special construction, consisting of a flexible strip 115, and a bi-metal strip 116 secured together by rivets 117, as shown (see Fig. 20). As is well known, bi-metal consists of sheets of two metal or dissimilar co-efficients of expansion, usually welded together to form one laminated sheet or strip. It has the property of exhibiting curvature when heated, the degree of such curvature being to a certain extent proportional to the change in temperature from the particular temperature at which the bi-metal is flat or straight. Metals commonly used in producing bi-metal are brass and steel, and brass and Monel metal.

At the outer end of the bi-metal strip 116 is mounted the movable contact 118, positioned to lie flat against the stationary contact 112 when their surfaces are in contact. The tongue 113 is conveniently mounted on a support 120 by means of a screw 121 and clamp 122. The support 120 is part of the governor bracket 108. Near the middle of the tongue is a hole into which is in-

75

- serted the swivel pin 123, having a hole into which is threaded one looped end of the governor spring 114. The governor bracket 108 is mounted on the disk 101 by two screws 119 at one end, which 5 screws terminate in the slip ring 105 making electrical contact therewith. The contact bracket 107 and the governor bracket 108 are insulated electrically, except when the contacts 112 and 118 are closed. A portion of the governor bracket 108 10 is upturned to form the support 124 upon which is mounted the flexible adjusting lever 125. The free end of the adjusting lever is turned inwardly and is perforated by a small hole into which is threaded a looped end of the spring 114 as shown. 15 Between the bent portion of the adjusting lever 125 and the support 124, the adjusting lever is pierced by a hole, through which is assembled the micrometer adjusting screw 126, screwed into the support member 127. 20 The operation of the governor is as follows: Assume that the governor is rotating in a counterclockwise direction as viewed in Fig. 18. At a particular speed, the centrifugal force on the tongue 113 will exceed the spring tension in the 25 spring 114, and the contacts 112—118 will open. When these contacts open, the resistance R2 is inserted in series with the motor as shown in Fig. 21. The motor is thereby slowed down, causing the contacts to close, again speeding up the 30 motor. This process is repeated many times a second, the motor not reaching a stable speed, but varying minutely above and below the speed at which the contacts open. This type of governor is well known, and it is to be observed that both 35 the inertia of and centrifugal force on the tongue 113 contribute to the regulating action. It has therefore been called a centrifugal-inertia governor. It is characterized by its sensitivity and accuracy of regulation. 40 The novel features of the present invention reside in the means for temperature compensation and for minor speed adjustment. It is evident that the tension in the spring 114 determines the speed to which the motor is regulated. An increase in the temperature of spring 114 results in 45 a slight decrease in its tension, lowering slightly the regulated speed of the motor. This effect is compensated for in two ways. The governor bracket 108 is held in position at one end by 50 screws 119, the other end being free to move endwise only. The tensioning lever 125 and the adjusting screw 126 are mounted at the free end of the governor bracket 108. As the temperature of the governor increases, the governor bracket 55 108 is extended endwise by thermal expansion, stretching to a slight extent the spring 114, thereby increasing its tension and compensating in part for the decrease in tension due to temperature. The compensation gained by this means is 60 limited, however, by the thermal expansion of the material of the governor bracket along its length, and since the length of wire in the spring is much greater than the length of the governor bracket, compensation over a considerable range 65 of temperature is not readily accomplished by this means alone. The second temperature compensation means is provided by the bi-metal strip 116 forming part of the tongue 113. As shown in Fig. 20, in exaggerated form, when the temperature 70 of the bi-metal strip 116 is increased, it curves convexly outward. Due to this curvature, the tension of the spring 114 is increased with increase of temperature, compensating for its normal loss of tension with increase of temperature. 75 By using proper bi-metal combinations and pro-

portions of parts, determinable by well understood methods, thermal compensation of the governor may be accomplished over a considerable range of temperature. With this improvement, the type of governor shown will regulate the speed 5 of the motor with a high degree of precision under various conditions of temperature.

Minor speed adjustments

It would appear that the resistance R2, commonly called the gap resistance, if sufficiently large to slow the motor down to the speed set by the governor, would have little effect on the speed set by the governor. Such is the case, but a minor change in speed does result from a comparatively large change in the value of the resistance R2. According to the present invention, this effect is utilized to accomplish minor adjustment of the motor speed, without mechanical adjustment of the governor, the value of R2 being 20 variable for that purpose.

It is to be noted that changing the value of the gap resistance R2 is not equivalent to introducing a similar resistance into other parts of the motor circuit. Resistance placed in series 25 with the motor, for example, has the same effect as a change of load, and is counteracted by the governor. The effect of such series resistance is also to impair the range of regulation of the governor. A relatively large change in the gap resistance R2 does not limit to any material extent the range of regulation of the governor, but does produce a minor change in the speed set by the governor.

In printing telegraph systems, it is sometimes 35 desirable to cause the sending instrument to run slower by a constant amount than does the receiving instrument, or vice versa. In the present invention a change in the gap resistance is utilized to effect the desired constant speed difference. For this purpose, as resistance R1 is placed 40 in series with the variable gap resistance R2 but is normally short circuited by the contacts 109—109'. When these contacts are closed, the motor speed is regulated by the governor gap resistance R2 as previously described. When the contacts are open, additional resistance is introduced in the gap, and minor but constant decrease in speed results. It is obvious that the same arrangement, considering as normal the 45 speed when contacts 109—109' are open, will produce a minor increase in speed when the contacts 109—109' are closed. The contacts 109—109' may consist of a switch, for local operation, or of the contacts of a relay for remote 50 control.

It is thus clear that the present invention provides a novel method of temperature compensation and minor speed control and adjustment for an electrical governor. The improved governor 60 herein described is highly accurate, rapid and sensitive in action, self-compensating for temperature changes, adapted to minor speed adjustments without stopping the governor or changing its mechanical adjustments, and particularly adapted to control of incremental speed 65 changes by remote control.

Spring link feature

As previously stated, the signal impulses and 70 operation impulses in a high speed printing telegraph are very brief in duration, and special provisions are necessary to assure certain response of relays and magnets to such brief impulses.

One of the features of the present invention 75

is the means provided to assure efficient operation of the key solenoids and the key release solenoid. The solenoid possesses the advantages of simplicity and low cost, and of a long operating stroke. It is well known, however, that solenoids are inherently sluggish in response as compared to relays and magnets having short air gaps, and it has heretofore been the practice to use magnets adapted to quick response in the operation of printing telegraph mechanisms. The Hughes magnet employed in the Hughes printing telegraph is a well known example.

In the present invention, the plunger of each solenoid is connected to the member which it actuates by a resilient member consisting of a spring link 184 as shown in Fig. 23. The spring link is of the extension type with looped ends, one loop being threaded through an eye in the reduced end of the plunger, the other loop being threaded through a hole in the associated lever as shown. When the solenoid is energized the spring link is stretched and the plunger is quickly attracted, permitting the air gap to be closed, increasing the pull on the plunger. Were a resilient connection between the plunger and actuated member not provided, the entire mass of the plunger, connecting link, and actuated member would have to be accelerated in order to close the air gap. Since the effective mass of the actuated member is greater than that of the plunger and spring link, the action of the plunger would of necessity be slower, and loss of the available magnetic energy could be utilized. As is well known, the pull on the plunger of a solenoid increases rapidly as the air gap is closed. The impact of the plunger is cushioned by the spring link and the pad 231, avoiding shocks to the mechanism.

The action of the spring link permits the key solenoid plunger to pull in without opening the key switch contacts, as explained under receiving operations, thus avoiding cutting off the energizing current before the completion of the current impulse.

Without further analysis, it will be perceived that manifold advantages are provided by the spring link feature.

Special space bar construction

All of the key levers of a typewriter, except the space key lever, are of substantially the same size and weight. The space bar normally extends across the greater part of the length of the keyboard, and is attached directly to the space key lever. While such construction is suitable for manual operation, for automatic operation by a magnet, the greater mass of the space bar and space lever would necessitate a more powerful magnet for operating this structure than is sufficient for the other key levers.

To overcome this difficulty, the special construction shown in Fig. 24 is used. The space key lever 220 is somewhat longer than the other keys, and has an extension 221, which extends beneath, but is not attached to, the space bar bail 222. Upon the bail 222 is pivotally mounted space bar 223. Not being attached to the space key lever 220, the space bar would normally tend to revolve about the bail 222, and would thus fall out of place. This tendency is corrected by the stem 224 which is attached to the space bar by screws 225 as shown, the lower end of stem 224 working in a slot 226 in bracket 227. A compression spring 228 is assembled on stem 224 between bracket 227 and washer 229, which bears against the shoulder 230 of stem 224. To prevent the

spring 228 from moving space bar 223 above its normal level, the upward travel of stem 224 is limited by suitable means, such as the cotter pin 231, assembled in a hole through stem 224 beneath bracket 227.

It will be apparent that by proper design, the spring 228 will support the weight of the space bar assembly without offering undue resistance to the touch of the operator. When operated manually the space bar is depressed as usual. When operated by the key magnet, however, the space bar remains in position, and only the space key lever 220 is pulled down. By means of this construction, normal manual operation of the space bar is provided, but for automatic operation, the power required is no greater than that required for the other keys, and the same quick and easy response is obtained without using a special larger key magnet.

Without further analysis, the foregoing will so fully reveal the gist of this invention that others can, by applying current knowledge, readily adapt it for various applications without omitting certain features which from the standpoint of prior art constitute essential characteristics of the generic or special aspects of this invention and therefore such adaptation should and is intended to be comprehended within the meaning or range of equivalency of the following claims.

What is claimed is as follows:

1. A communication system of the character described comprising, in combination, a plurality of stations each having tele-registering mechanisms and associated rotary distributors normally at rest, means at each station for sending or responding to periodic control impulses for starting the rotary distributors and operating said distributors in synchronism and means thereat for sending or responding to aperiodic character control impulses, and means for conditioning one station to be responsive to the impulses sent by another station.

2. A communication system of the character described comprising, in combination, a plurality of stations, each having a tele-registering device and a plurality of circuits associated therewith, and means to condition said circuits periodically and in a definite sequence, means associated with each device and circuits for sending or responding to periodic circuit control impulses and aperiodic register control impulses, and means for controlling one device and associated circuits to be responsive to the impulses sent by another device and associated circuits.

3. A communication system of the character described comprising, in combination, a plurality of stations, each having a typewriting device and an associated distributor for sending or responding to control impulses, means for conditioning one station for transmitting the control impulses and means for conditioning another station for receiving the control impulses, and means at each station whereby operation of the said conditioning means at the receiving station is effective to signal the transmitting station without operation of the conditioning means thereat.

4. A communication system of the character described comprising, in combination, a plurality of stations, each having a typewriting device and an associated rotary distributor for sending or responding to control impulses, a signalling device at each station, means for conditioning one station for transmitting the control impulses and at the same time conditioning the signalling means thereat to be responsive to signalling means thereat to be responsive to sig-

- signalling impulses, and means for conditioning another station for receiving the control impulses and at the same time conditioning the signalling device thereat so as not to be responsive to signalling impulses, and means associated with the signalling devices whereby operation of the said conditioning means at the receiver is effective to transmit signalling impulses to operate the signalling device at the said transmitting station.
10. 5. A communication system of the character described comprising, in combination, a plurality of stations; typewriting means and an impulse distributing control circuit associated therewith, and an additional control circuit including
15. thermionic means at each station; a control device at each station to condition the said means and control circuits thereat for either transmitting or receiving signal impulses, said device including means so that upon a predetermined
20. operation thereof at one of the said stations the typewriting means and said control circuits are conditioned for transmitting the signal impulses by controlling the said distributing circuit upon operation of the typewriting means, and additional means included in said control device so that upon a different predetermined operation thereof at the other said station the typewriting means and said control circuits are conditioned for receiving the signal impulses by controlling
25. the said typewriting means upon impression of the signals upon the said distributing circuit and additional control circuit.
30. 6. A communication system of the character

described comprising, in combination, typewriting means including operable keys to send or respond to signal impulses and comprising key operated switching means to initiate the signal impulses and key actuating means operated by the signal impulses, means for connecting said switching means and actuating means so that when the switching means are inoperative the actuating means are in condition to be operated by the signal impulses and upon operation of the switching means signal impulses are initiated and the said actuating means are disconnected from said switching means.

7. A communication system of the character described comprising, in combination, typewriting means including operable keys, and key operated circuit conditioning means and key actuating means associated therewith, signal transmitting and receiving means, and positionable control means associated with said typewriting means to control the circuit conditioning means and signal means when set in one position to initiate and transmit signal impulses upon operation of the keys, and when set in a second position to control the key actuating means and signal means so as to operate the said actuating means upon receipt of the signal impulses, and when set in a third position to render said circuit conditioning means, key actuating means and said signal means inoperative thereby conditioning the typewriting means for typing conditions.

HARRY J. NICHOLS.
